United States Patent Office

Des. 185,483
Patented June 9, 1959

185,483

SHIRT FOLDING BOARD

Russell A. Ziegler, Wilton, Conn.

Application September 12, 1958, Serial No. 52,628

Term of patent 14 years

(Cl. D49—1)

FIG. 1

FIG. 2

FIG. 3

Fig. 1 is a perspective view of a shirt folding board embodying my new designs;

Fig. 2 is an elevation view taken from the top of Fig. 1; and

Fig. 3 is a side elevation view, thereof.

I claim:

The ornamental design for a shirt folding board, as shown.
